UNITED STATES PATENT OFFICE.

JAY F. SMITH, OF HOTCHKISS, COLORADO, ASSIGNOR OF ONE-THIRD TO MILO F. TOWNE
AND ONE-THIRD TO WATSON S. COBURN, BOTH OF HOTCHKISS, COLORADO.

BOX-PRESS.

1,105,463.

Specification of Letters Patent. Patented July 28, 1914.

Application filed November 8, 1913. Serial No. 799,977.

To all whom it may concern:

Be it known that I, JAY F. SMITH, a citizen of the United States, residing at Hotchkiss, in the county of Delta and State of

Colorado, have invented new and useful Improvements in Box-Presses, of which the following is a specification.

The invention relates to presses, and more particularly to the class of box presses.

10 The primary object of the invention is the provision of a press wherein the covers or lids to fruit or other boxes can be positioned with relation to the body of the box so that the same can be nailed thereto in a ready and convenient manner.

Another object of the invention is the provision of a press of this character wherein the lid or cover of a box will be automatically adjusted on the body of the said box, and the metal straps held in position so that both the lid and straps can be fastened for the securing of a lid or cover on the said box by nailing or otherwise fastening the same.

25 A further object of the invention is the provision of a press of this character wherein the body of the box will be held in proper position for the application of the cover or lid thereto, which is also firmly held and automatically clamped to permit the nailing of the cover or lid on the body of the box, the construction of the press being of novel form and is readily and easily operated.

35 A still further object of the invention is the provision of a press of this character which is simple in construction, thoroughly reliable and efficient in operation, and inexpensive in manufacture.

With these and other objects in view, the 40 invention consists in the construction, combination and arrangement of parts as will be hereinafter fully described, illustrated in the accompanying drawing, and pointed out in the claims hereunto appended.

45 In the drawings: Figure 1 is a side elevation of a press constructed in accordance with the invention, the same being in position for receiving a box. Fig. 2 is a front elevation thereof. Fig. 3 is a top plan view 50 showing a box and cover clamped in the press. Fig. 4 is a vertical sectional view through the press. Fig. 5 is a front eleva-

tion of a modified form of press. Fig. 6 is a vertical sectional view through the same. Fig. 7 is a vertical transverse sectional view 55 thereof. Fig. 8 is a side elevation.

Similar reference characters indicate corresponding parts throughout the several views in the drawings.

Referring to the drawings in detail, the 60 numeral 10 designates the base sills, 11 the spaced vertical side posts, 12 the end cross bars, and 13 the longitudinal bars which constitute the frame of the press, the posts 11 being secured to the base sills 10 in any 65 suitable manner, and likewise the bars 12 and 13 are secured to the said posts in any preferred manner. Extending from one end cross bar 12 to the other are downwardly bowed spaced parallel guide rails 14 which 70 are secured to the said bars 12, while connected to the upper edges of the latter bars are bearing strips 15 on which rest the body of a box when positioned upon the frame, the rails 14 being designed to guide the box 75 when sliding the same on the frame. Mounted at the upper ends of the posts 11 are retaining cleats 16 which serve to hold the box against displacement when resting upon the bearing strips 15 contiguous to the 80 said cleats.

Secured to the rearmost posts 11 near the base sills 10 is a brace piece 17 to which is connected medially thereof a hanger 18 forming a fulcrum for a foot operated 85 treadle or lever 19, the same being extended forwardly beyond the front of the frame and is adapted to be operated for actuating the clamping mechanism for the cover or lid of the box body hereinafter fully described. 90

The clamping mechanism for the cover or lid comprises a pair of vertically arranged standards or uprights 20 which are formed with slots 21 near their lower ends, the said slots being designed to receive bolt members 95 22 which are fastened in the rearmost posts 11 and carry the usual nuts 23, which secure the uprights in vertically adjusted position. Fixed to the rearmost post 11 are brackets 24 with which engage the uprights 20, the 100 said brackets 24 being formed with offset rear ends 25 which receive the said uprights, and to these offset ends are pivoted links 26, the same being also connected to draw bars

27 which are connected together at their lower ends through the medium of a cross bar 28 carrying a coupling 29 engaged in the foot lever or treadle 19, the said draw bars 27 being connected to the clamping mechanism for the cover or lid of the box.

5 Mounted in the upper ends of the uprights 20 is a cross rod 30 to which are swingingly connected a pair of arms 31 carrying substantially inverted U-shaped clamping frames 32, the forward ends of which are connected to the arms, while the rear ends thereof are connected to the rod 30, and these frames are adapted to engage the lid or cover of the box body near opposite ends thereof so that 10 on the lowering of the draw bars 27 the lid or cover is brought into alinement with the box body and clamped as well as pressing the same onto the body of the box.

15 20 Connected at spaced intervals on the arms 31 are substantially inverted L-shaped fingers 33 which are adapted to engage the metallic straps ordinarily employed for the fastening of the lid or cover to the box body so as to hold the strips across the end portions of the lid or cover whereby they 25 may be fastened by the nailing of the same thereon. Mounted upon the members securing the fingers 33 on the arms are leaf springs 34 which are formed at their free 30 ends with notches 35 receiving the right angular portions of the fingers 33 so that the springs will be guided thereby, and are adapted to work against the ends of the lid 35 or cover for the adjustment thereof longitudinally with relation to the box body and also sustain it in adjusted position so that the lid or cover can be readily and conveniently nailed to the box.

40 45 Connected to the front longitudinal bar 13 of the frame is a latch bar 36 having rack teeth 37 arranged in the path of a keeper plate 38 fixed to the lever or treadle 19 so that when pressure is applied to the latter the keeper plate 38 will adjustably engage the teeth 37 for sustaining the treadle or lever lowered to hold the clamping mechanism in clamping relation to the box body when resting upon the frame.

50 55 Suitably connected to the rearmost longitudinal rail 13 of the frame are a pair of coiled retractile springs 39 which are also connected to the lever or treadle and serve to lift the same when released so that the clamping mechanism will be raised to remove the box from the frame after the cover or lid has been nailed thereto, and also to permit the placing of another box body upon the frame whereby its lid or cover 60 can be clamped in a manner hereinbefore described, and nailed thereto.

In Figs. 5 to 8 there is shown a slight modification of the invention wherein the frame has detachably connected thereto supplemental end pieces 40, the same carrying

cleats 41 which are detachably connected with the end cross bars 42 of the frame, the said supplemental end pieces 40 being used when it is desired to clamp and nail the cover or lid to a shallow box, for instance, a peach box. The supplemental pieces 40 have mounted thereon spaced parallel downwardly bowed guide rails 43 and retaining cleats 44 similar to those hereinbefore described.

75 From the foregoing it is thought that the construction and manner of operation of the device will be clearly understood, and therefore a more extended explanation has been omitted.

80 What is claimed is:

1. A machine of the class described comprising a frame having a box rest, guide rails supported by the frame and adapted to guide a box upon the rest, vertical standards connected to the ends of the frames, arms swingingly connected to the upper ends of the standards, clamping frames carried by the arms, a foot treadle connected with the frame, means connecting the foot treadle to the swinging arms whereby on the lowering of the treadle the clamping frames will act upon the cover of the box for pressing it thereon, and means carried by the frame for locking the treadle in lowered position. 95

2. A machine of the class described comprising a frame having a box rest, guide rails supported by the frame and adapted to guide a box upon the rest, vertical standards connected to the ends of the frames, arms swingingly connected to the upper ends of the standards, clamping frames carried by the arms, a foot treadle connected with the frame, means connecting the foot treadle to the swinging arms whereby on the lowering of the treadle the clamping frames will act upon the cover of the box for pressing it thereon, means carried by the frame for locking the treadle in lowered position, and clamping fingers carried by the arms and engageable with metallic straps for holding the same in proper relation to the cover of a box. 105

3. A machine of the class described comprising a frame having a box rest, guide rails supported by the frame and adapted to guide a box upon the rest, vertical standards connected to the ends of the frames, arms swingingly connected to the upper ends of the standards, clamping frames carried by the arms, a foot treadle connected with the frame, means connecting the foot treadle to the swinging arms whereby on the lowering of the treadle the clamping frames will act upon the cover of the box for pressing it thereon, means carried by the frame for locking the treadle in lowered position, clamping fingers carried by the arms and engageable with metallic straps for holding the same in proper relation to the cover of a box. 115

the cover of a box, and resilient members carried by the arms for automatically adjusting the cover of the box with relation to the latter on the lowering of the clamping frames.

5 4. A machine of the class described comprising a frame having a box rest, guide rails supported by the frame and adapted to guide a box upon the rest, vertical standards connected to the ends of the frames, arms swingingly connected to the upper ends of the standards, clamping frames carried by the arms, a foot treadle connected with the frame, means connecting the foot treadle to the swinging arms whereby on the lowering of the treadle the clamping frames will act upon the cover of the box for pressing it thereon, means carried by the frame for locking the treadle in lowered position, 10 clamping fingers carried by the arms and engageable with metallic straps for holding the same in proper relation to the cover of a box, resilient members carried by the arms for automatically adjusting the cover of the 15 box with relation to the latter on the lowering of the clamping frames, and brackets carried by the frame and engaged by the standards, 20

25 5. A machine of the class described comprising a frame having a box rest, guide rails supported by the frame and adapted to guide a box upon the rest, vertical standards connected to the ends of the frames, arms swingingly connected to the upper ends of the standards, clamping frames carried by the arms, a foot treadle connected with the frame, means connecting the foot treadle to the swinging arms whereby on the lowering of the treadle the clamping frames will act upon the cover of the box for pressing it thereon, means carried by the frame for locking the treadle in lowered position, 30 clamping fingers carried by the arms and engageable with metallic straps for holding the same in proper relation to the cover of a box, resilient members carried by the arms for automatically adjusting the cover of the 35 box with relation to the latter on the lowering of the clamping frames, and brackets carried by the frame and engaged by the standards.

35 6. A machine of the class described comprising a frame having a box rest, guide rails supported by the frame and adapted to guide a box upon the rest, vertical standards connected to the ends of the frames, arms swingingly connected to the upper ends of the standards, clamping frames carried by the arms, a foot treadle connected with the frame, means connecting the foot treadle to the swinging arms whereby on the lowering of the treadle the clamping frames will act upon the cover of the box for pressing it thereon, means carried by the frame for locking the treadle in lowered position, 40 clamping fingers carried by the arms and engageable with metallic straps for holding the same in proper relation to the cover of a box, resilient members carried by the arms for automatically adjusting the cover of the 45 box with relation to the latter on the lowering of the clamping frames, and brackets carried by the frame and engaged by the standards, and linked connections between the brackets and the means connecting the treadle with the swinging arms.

45 7. A machine of the class described comprising a frame having a box rest, guide rails supported by the frame and adapted to guide a box upon the rest, vertical standards connected to the ends of the frames, arms swingingly connected to the upper ends of the standards, clamping frames carried by the arms, a foot treadle connected with the frame, means connecting the foot treadle to the swinging arms whereby on the lowering of the treadle the clamping frames will act upon the cover of the box for pressing it thereon, means carried by the frame for locking the treadle in lowered position, 50 clamping fingers carried by the arms and engageable with metallic straps for holding the same in proper relation to the cover of a box, resilient members carried by the arms for automatically adjusting the cover of the 55 box with relation to the latter on the lower-

thereon, means carried by the frame for locking the treadle in lowered position, clamping fingers carried by the arms and engageable with metallic straps for holding the same in proper relation to the cover of a box, resilient members carried by the arms for automatically adjusting the cover of the 70 box with relation to the latter on the lowering of the clamping frames, brackets carried by the frame and engaged by the standards, 75

75 linked connections between the brackets and the means connecting the treadle with the swinging arms, and retractile means connected with the frame and the treadle for automatically lifting the same when released.

80 7. A machine of the class described comprising a frame having a box rest, guide rails supported by the frame and adapted to guide a box upon the rest, vertical standards connected to the ends of the frames, arms swingingly connected to the upper ends of the standards, clamping frames carried by the arms, a foot treadle connected with the frame, means connecting the foot treadle to the swinging arms whereby on the lowering of the treadle the clamping frames will act upon the cover of the box for pressing it thereon, means carried by the frame for locking the treadle in lowered position, 85 clamping fingers carried by the arms and engageable with metallic straps for holding the same in proper relation to the cover of a box, resilient members carried by the arms for automatically adjusting the cover of the 90 box with relation to the latter on the lowering of the clamping frames, and brackets carried by the frame and engaged by the standards, linked connections between the brackets and the means connecting the treadle with the 95 swinging arms, retractile means connected with the frame and the treadle for automatically lifting the same when released, and removable end pieces for the said frame and having box receiving rests.

100 8. A machine of the class described comprising a frame having a box rest, guide rails supported by the frame and adapted to guide a box upon the rest, vertical standards connected to the ends of the frames, arms swingingly connected to the upper ends of the standards, clamping frames carried by the arms, a foot treadle connected with the frame, means connecting the foot treadle to the swinging arms whereby on the lowering of the treadle the clamping frames will act upon the cover of the box for pressing it thereon, means carried by the frame for locking the treadle in lowered position, 105 clamping fingers carried by the arms and engageable with metallic straps for holding the same in proper relation to the cover of a box, resilient members carried by the arms for automatically adjusting the cover of the 110 box with relation to the latter on the lower-

ing of the clamping frames, brackets carried by the frame and engaged by the standards, linked connections between the bracket and the means connecting the treadle with
5 the swinging arms, retractile means connected with the frame and the treadle for automatically lifting the same when released, removable end pieces for the said frame and having box receiving rests, and guide rails

carried by the removable end pieces and 10 adapted to guide a box upon the rests.

In testimony whereof I affix my signature in presence of two witnesses.

JAY F. SMITH.
